SEWING MACHINE

Filed July 13, 1927

UNITED STATES PATENT OFFICE

HUGH M. STEPHENSON, OF FORT WAYNE, INDIANA, ASSIGNOR TO GENERAL ELECTRIC COMPANY, A CORPORATION OF NEW YORK

SEWING MACHINE

Application filed July 13, 1927. Serial No. 205,479.

My invention relates generally to sewing machines and more particularly to an improved rotary take-up mechanism therefor.

5 Rotary take-up mechanisms are desirable, particularly in high speed sewing machines, because of the simplicity of their structure and the absence of heavy vibrating parts. However, these mechanisms have been subject to the disadvantage that the thread has 10 not been positively controlled throughout the cycle of their operation and as a result the thread has been broken or snarled frequently during the operation of the machines. Breaking of the thread has usually 15 been accompanied by the ends of the broken thread being wound up in the mechanism which occasions considerable delay and trouble in rethreading the machine. Moreover, rotary take-ups as heretofore proposed have 20 been clumsy in construction and difficult to thread so that they have not been used on slow speed sewing machines of the domestic type, although the fact that they operate with little or no vibration makes them 25 desirable for this purpose.

An object of my invention is to provide a rotary take-up which positively controls the thread throughout the cycle of its operation so that the possibility of breaking or 30 snarling the thread during the operation of the machine will be minimized.

Another object of my invention is to provide a rotary take-up of such a construction that in case the thread is broken the ends 35 will not become entangled in the rotating elements of the device.

Another object of my invention is to provide a compact and simplified take-up mechanism which is adapted for use on sewing machines of all types.

40 A further object of my invention is to vary the operation of the take-up in response to changes in the thickness of the material being sewn in the machine.

45 Further objects and advantages of my invention will become apparent as the description proceeds, and the features of novelty which characterize my invention will be 50 pointed out with particularity in the claims

annexed to and forming a part of this specification.

55 My invention will be more fully set forth in the following description referring to the accompanying drawing, in which Fig. 1 is a side elevation of a sewing machine embodying my invention, and Fig. 2 is a perspective view of my improved take-up and related mechanism.

60 Referring to the drawing, the sewing machine in connection with which I have illustrated my invention comprises a bed-plate 10 having an overhanging arm 11 thereon for supporting a needle-bar 12, presser-foot 13, and my improved take-up mechanism. The 65 needle-bar and presser-foot cooperate with a loop-taker 14 and feed-dog 15 in forming stitches in the usual manner during the operation of the machine, and thread is supplied to the needle 12^a through a tensioning 70 device 20 and my improved take-up which accurately controls the thread. The needle-bar 12 is operated in the necessary time relation to the loop-taker 14 and feed-dog 15 by a horizontal shaft 16 extending through the arm 11 75 which is connected by suitable shafts and gearing to the horizontal shaft 17 beneath the bed plate 10 on which the loop-taker 14 is mounted. The stitch forming mechanism, including the take-up, needle-bar 12, presser- 80 foot 13, loop-taker 14 and feed-dog 15, is driven by an electric motor 18 supported underneath the bed-plate 10, although it may be driven, if desired, by a treadle mechanism provided with a belt extending over pulley 85 19, or by any other suitable means.

85 My improved take-up mechanism comprises a stationary thread-guide attached to the arm 11 at 21 and 22 adapted to engage the thread at 23 and 24, and a rotatable plate 25 secured to a crank 26 which operates the needle-bar 12 by the connecting rod 27. The needle-bar crank is fixed on the shaft 16, and the rotatable plate 25 is arranged with its center substantially in alignment with the 90 shaft 16 so that the plate will be substantially balanced. The plate 25 is provided with longitudinally movable thread engaging pins 28 which are arranged in openings 28^a in the plate in such relation thereto and 100

the thread-guide as to pass between the thread engaging portions 23 and 24 and engage the thread 29 to complete the stitch in the material being sewn and form loops 30 (see Fig. 2) extending from the thread guide at 23 and 24. After the thread loops 30 have been pulled out far enough to take-up the amount of thread necessary to form a loop which can be passed around the bobbin case 14^a by the loop-taker 14 and form the succeeding stitch, the pins 28 are retracted into the plate 25 far enough to disengage the thread loops 30 and a thread loop is passed around the bobbin case by the loop-taker 14 which straightens the loops 30 between the portions 23 and 24 of the thread guide. In order to accurately control the released thread loops 30 and prevent them from becoming twisted, which would break the thread, light follower springs 31 are supported on the thread-guide which are biased to a position angularly displaced from the thread engaging portions 23 and 24 of the thread-guide in the direction of rotation of the plate 25 (indicated by the arrow in Fig. 2). By this arrangement the pins 28 form the loops 30 and the springs 31 follow the enlarging thread loops outwardly from the thread-guide portions 23 and 24. The force exerted by the follower springs 31 tending to maintain the thread loops 30 is not great enough to pull thread through the tensioning device 20 or substantially affect the operation of the loop-taker 14, so that when the thread loops are released the loop-taker straightens the thread loops against the action of the follower springs 31 and brings the latter into alignment with the thread-guide portions 23 and 24. It will be noted that although this construction is not enclosed it accurately controls the thread loops in the take-up, which permits the take-up to be readily threaded, and which minimizes the possibility of the thread being broken and being wound up on the pins 28 projecting through the rotating plate 25 during the operation of the machine.

In order to provide for longitudinal movement of the pins 28 so that they can be projected and retracted through the openings 28^a in the plate 25, they are mounted on a plate 32 which is secured to a sleeve 33 slidable longitudinally on the crank 26. The longitudinal movement of the sleeve 33 on the crank 26, and the corresponding movements of the pins 28 for moving them so as to engage and disengage the thread in proper time relation to the movement of the loop-taker 14, is controlled by a non-rotatable cam 34 which is supported on the shaft 16 and arranged so that it can be angularly adjusted. The cam 34 controls the sleeve 33 and the pins 28 by means of a shaft 37 slidably fitted in the bore 26^a of the crank 26, one end of the shaft 37 having a roller 35

attached thereto by means of a bracket 36 and the other end being connected to the sleeve 33 by a pin 38 extending through a longitudinal slot 39 in the crank 26. The shaft 37, which is rotated about the cam 34 by the crank 26, is prevented from turning in the bore 26^a by the pin 38 engaging the sides of the slot 39, although the shaft 37 can reciprocate in the bore 26^a under the action of the cam 34 and the roller 35 engaging the same as the latter is rotated about the former by the movement of the crank 26. The cam 34 is so designed that the pins 28 are moved outwardly so as to engage the thread 29 passing through the guide portions 23 and 24 as they pass the same, and when the thread loops 30 are pulled out enough to form a loop which can be passed around the bobbin case 14^a by the loop-taker 14 in the sewing operation the cam 34 retracts the pins 28 releasing the loops. It will now be apparent that if the cam 34 is shifted angularly the timing of the release of the thread loops 30 from the pins 28 can be varied to take place when a greater or lesser amount of thread is pulled out in the thread loops 30.

It is well understood by those skilled in the art that the take-up mechanism should take up a greater amount of thread when a thick piece of material is being sewn in the machine than when a thin piece is being sewn. In order to do this in my improved mechanism, I connect the cam 34 to the presser bar 13^a by an arm 40 which is pivoted on the cam 34 at 41, so that as the presser-foot 13 is raised above the feed-dog 15 by the passage of material between the presser-foot and the feed-dog, the cam 34 will be moved angularly on the shaft 16 in proportion to the thickness of the material. This causes the pins 28 to disengage the thread loops 30 at a distance from the guide portions 23 and 24 of the thread guides proportional to the thickness of the material and causes enough thread to be taken up to properly form the stitch and to pass the thread loop around the bobbin case.

In the operation of the sewing machine illustrated, when the rotatable plate 25 is rotated in a direction indicated by the arrow in Fig. 2 slightly beyond the position in which it is shown, the pins 28 are retracted by the cam 34 which releases the thread loops 30. Upon the release of the thread loops 30 the needle 12^a passes the thread through the material being sewn and into engagement with the loop-taker 14. The loop-taker then passes the thread loop around the bobbin case 14^a containing the lower thread and straightens the thread loops 30 between the portions 23 and 24 of the thread guide against the action of the springs 31. The loop-taker 14 then releases the loop which is around the bobbin case 14^a and by this time the pins 28 are pro-

jected through the plate 25 and rotated so as to engage the thread 29 extending through the portions 23 and 24 of the thread guide. Further movement of the mechanism causes the pins 28 to pull out the thread loops 30 as shown in Fig. 2 and thereby take up the loop around the bobbin case 14^a which is released from the loop-taker 14. The pins 28 are rotated by the plate 25 until they complete the 10 stitch and take up enough thread to form a loop which can be passed around the bobbin case 14^a by the loop-taker 14 in forming the succeeding stitch. The amount of thread which is taken up by the pins 28 in this manner in addition to that required to form a loop which will pass around the bobbin case is controlled by the material being sewn which varies the height of the presser-foot above the feed-dog 15 as the thickness of the material 15 varies and which correspondingly varies the position of the cam 34 and the amount of thread taken up.

In view of the foregoing it will be clear that I have produced an improved rotary 20 take-up for sewing machines which accurately controls the thread through the cycle of its operation, which is simple and compact, and which minimizes the possibility of the thread becoming entangled in the take-up in 25 the event the thread is broken during the operation of the machine.

Although I have shown one form of my invention in connection with an electric rotary center bobbin sewing machine, it is obvious 30 that modifications can be made and that it is applicable as well to other types of sewing machines. I desire it to be understood, therefore, that my invention is not limited to the particular arrangement shown and described, 35 and I intend in the appended claims to cover all modifications which do not depart from the spirit and scope of my invention.

What I claim as new and desire to secure by Letters Patent of the United States, is:—

45 1. In a sewing machine take-up, means for guiding a thread, a rotatable element, means for connecting the thread to said rotatable element when the latter is in one position to form a thread loop, means for disconnecting the thread loop from said rotatable element when the latter is in another position, and means movable in a direction opposite to the movement of said rotatable element for guiding the released thread loop.

55 2. In a sewing machine take-up, means for guiding a thread, a rotatable element, means for connecting the thread to said rotatable element when the latter is in one position to form a thread loop, means for disconnecting the thread loop from said rotatable element when the latter is in another position, and means including a movable spring for guiding the released thread loop.

60 3. In a sewing machine take-up, means for guiding a thread, a rotatable element, means

for connecting the thread to said rotatable element when the latter is in one position to form a thread loop, means for disconnecting the thread loop from said rotatable element when the latter is in another position, and means including a spring tending to move in the direction of rotation of said rotatable element for guiding the released thread loop.

70 4. In a sewing machine, a take-up including a rotating plate, a stationary thread guide extending adjacent said rotating plate, a pin extending through said plate adapted to engage a thread carried by said thread guide, another plate on which said pin is mounted, and means for moving said plates relative to each other to retract said pin into said rotating plate and release the thread.

75 5. In a sewing machine take-up, means for forming a thread loop, means for releasing said thread loop from said first mentioned means, and means for guiding the thread loop including a spring tending to maintain the same.

80 6. In a sewing machine, a take-up comprising two stationary thread guides, means for forming a thread loop extending between said thread guides, means for releasing the thread loop from the first mentioned means, and a movable thread guide provided with a spring exerting such force tending to maintain the loop that the tension of the thread 85 pulls said movable thread guide into alignment with said stationary thread guides and straightens the loop.

90 7. In a sewing machine, a take-up including a rotatable plate, a stationary thread guide extending across said rotatable plate, a movable thread guide, a spring tending to retain said movable thread guide in a position displaced from said stationary thread 95 guide, said spring exerting such force that said movable thread guide is brought into alignment with said stationary thread guide by the tension of the thread thereon against the action of said spring, means on said rotatable plate for engaging the thread to form a loop therein extending from said stationary thread guide, and means for releasing the thread after the means for engaging the thread has been displaced from said stationary 100 thread guide, so that the thread loop is straightened and the movable thread guide is brought into alignment with the stationary thread guide by the tension of the thread.

105 8. In a sewing machine stitch forming mechanism, a needle bar crank, a rotatable member supported by said crank, means carried by said member for engaging a thread, and means for disengaging said last mentioned means from the thread, including an 110 extension through said needle bar crank.

115 9. In a sewing machine stitch forming mechanism, a needle bar actuating shaft having a crank pin thereon, a rotatable plate mounted on said crank pin, a thread guide ad- 120

125

130

jacent said rotatable plate, pins extending through said rotatable plate for engaging the thread in said thread guide, means for retracting said pins into said rotatable plate for disengaging the thread from said pins 5 including a stationary cam surrounding said needle bar actuating shaft, and an extension through said crank pin.

10. In a sewing machine stitch forming mechanism including a presser-bar, a needle bar actuating shaft having a crank pin thereon, a rotatable plate mounted on said crank pin, a thread guide adjacent said rotatable plate, pins extending through said rotatable plate for engaging the thread in said thread guide, means for retracting said pins into said rotatable plate for disengaging the thread from said pins including a stationary cam surrounding said needle bar actuating 15 shaft and an extension through said crank pin, said last mentioned means being controlled by said presser-bar.

11. In a sewing machine stitch forming mechanism, a needle bar actuating shaft having a crank thereon, means carried by said crank for taking up the thread in said mechanism, and means for controlling the take-up means including a shaft extending into said crank and a sleeve on said crank connected to said shaft.

In witness whereof, I have hereunto set my hand this 11th day of July, 1927.

HUGH M. STEPHENSON.
